DESIGN FOR A SHOE SOLE

Albert L. Murray, Auburn, Ind.

Application December 21, 1933, Serial No. 50,176

Term of patent 14 years

To all whom it may concern:

Be it known that I, ALBERT L. MURRAY, a citizen of the United States, residing at Auburn, in the county of De Kalb and State of Indiana, have invented a new, original, and ornamental Design for Shoe Soles, of which the following is a specification, reference being had to the accompanying drawing, forming part thereof.

Figure 1 is a plan view of a shoe sole showing my new design and Fig. 2 a cross-section on line 2—2 of Fig. 1.

I claim:

The ornamental design for a shoe sole as shown.

ALBERT L. MURRAY.
